PROCESS OF MAKING CLOSURE CAPS

William J. Keith, Brookline, Mass., assignor to
 Keith-Peabody, Inc., Brookline, Mass., a corporation of Massachusetts

Application October 13, 1943, Serial No. 506,096

6 Claims. (Cl. 93—36)

1

This invention relates to a process of making improved closure caps of the character used for closing and sealing containers, such as jars, bottles, cans and other such receptacles.

The object of this invention is to improve the construction of such closure caps, to enable them to be manufactured of paper or other non-metallic material in a simple and effective manner, and yet providing the necessary strength and rigidity for practical use.

A further object of the invention is to improve the side wall structure of a closure cap, to enable it to be manufactured either of multiple shells drawn to proper shape, or of convolutely wound paper ribbon with a shell, and to form therein a thread groove of sufficient strength and rigidity for effectively securing the cap in sealed relation on the container.

These objects are accomplished in the preferred embodiment of the invention by shaping a paper shell of the desired size, forming a thread groove in the flange portion thereof, and then fitting another shell or shells, or a convolutely wound sleeve or cylinder, over the first shell and rolling a thread groove in the second shell or cylinder, so as to fit into the first thread groove, whereby the side wall structure will be reenforced for requisite rigidity, and a thread groove will be formed also of substantial rigidity and strength effective for securing the cap on the container. This enables the cap to be manufactured with automatic machinery in a simple and expeditious manner, and although made of paper or such non-metallic material, it has the desired strength and rigidity effective for the purpose. It may be decorated or illustrated with any desired designs, trade-marks or the like, and where the inside of the cap is coated, the liner usually required may be entirely omitted.

The invention is illustrated in different embodiments in the accompanying drawings, in which:

Fig. 1 is a cross section through a single paper shell initially formed;

Fig. 2 is a similar view showing the formation of a thread groove therein;

Fig. 3 is a side elevation of the first shell showing in section a second shell fitted thereover;

Fig. 4 is a cross section through the combined shells and interfitting thread grooves;

Fig. 5 is a similar view with a convolutely wound ribbon cylinder covering the first shell;

Fig. 6 is a cross section similar to Fig. 4, with a covering shell thereover;

Fig. 7 is a similar view showing another form

2

of decorative covering on the combined shells;

Fig. 8 is a similar view showing a surrounding convolutely wound ribbon thereon; and

Fig. 9 is a detail sectional view showing a further modification of the closure cap.

This invention involves the formation of the closure cap from a plurality of paper shells or cylindrical structures which are fitted together, and separately formed to provide the required thread groove therein. These may be formed individually of single plies of paper, or each shell or cylindrical section may be made up of multiple plies, although the second shell or cylindrical section will be applied over the initial shell or section after the latter is completely formed.

I have shown in Fig. 1, the first shell formed of paper or other non-metallic material. This shell may be formed from a single sheet, and drawn or shaped by dies to provide a top 1 with a surrounding wall 2 formed by an integral flange on the top 1. When formed with dies, the paper may be shaped quickly and without objectionable wrinkles, enabling the caps to be formed at high speed on automatic machines and to be handled with a minimum of effort.

After thus forming the flange on the disc, a thread groove 3 is rolled into the side wall flange 2, so as to form a thread, or partial thread, of desired characteristics on the inner wall of the cap, by impressing this in the relatively thin material of the flange.

Thereafter, a second paper shell, designated generally by the numeral 4, is fitted over the shell 1—2. A shell 4 is similarly made of relatively thin paper drawn to cylindrical shape, as shown in Fig. 3, and only slightly larger than the shell 1—2 to fit tightly thereover. The shell 4 may also be formed with dies, and being of relatively thin paper or the like, may be applied effectively to the first shell. Either the first or the second shell may be coated on the abutting face with an adhesive suitable to secure the shells directly together, preferably throughout their contacting area, or air drying plastics or thermo-plastics may be used to bind the shells directly together, securing positive stability with rigid top and side walls.

After thus fitting the second shell 4 over the first shell, and before the adhesive or other securing material has set, a thread groove 5 is rolled or impressed into the first thread groove 3, as shown in Fig. 4, thus providing a multiple ply thread groove within the cap, the parts of which are adhesively or otherwise rigidly secured together.

Instead of using a complete shell to fit over

the first shell, a cylindrical portion may be used, as shown in Fig. 5, where substantial end wall rigidity is not required. In this form, the cylindrical portion is designated generally at 6 surrounding the wall flange 2. The cylindrical portion is formed preferably by a convolutely wound paper ribbon, as shown at 16 in Fig. 9, which is adhesively applied and wound directly on the wall flange 2, of multiple convolutions of thin material to provide the desired strength in the side wall of the cap. Such a convolutely wound ribbon may be used upon a paper wall, although it is difficult to start the winding of a paper ribbon convolutely upon a metal form, thus lending it effectively to this method of construction. After thus forming the cylindrical portion 6, a thread groove 7 is rolled or impressed in complementary relation in the thread groove 3.

After thus forming the shell structure of multiple plies of side walls, a finishing surface is provided, such as by means of a third shell 8, shown in Fig. 6, which is then applied to the shells 1—2 and 4. The shell 8 should be plain without thread in the flange portion thereof and effectively covers the impressed thread in the first two shells. This creates a double cap appearance by completely concealing the threads on the inside shells or convolutely wound ribbon. The decoration, ornamentation or trade-mark illustration may be applied directly on the shell 8 either at the top thereof or on the surrounding wall or both, which may be applied easily either before or after the formation of this finishing shell 8.

If the additional top wall structure is not required, indicated at 17 in Fig. 9, the finishing shell may be formed by a convolutely wound ribbon, shown at 9 in Fig. 8, applied directly over the shells 1—2 and 4.

The structure of Fig. 8, including two shells and a surrounding convolutely wound paper ribbon, may be further covered for additional strength or ornamentation with a decorated or plain paper ribbon shown at 10 in Fig. 7, having an inturned flange 11 folded over at the top edge of the formed cap and covered by a decorated or plain disc 12, as shown in Fig. 7. Thus two or more shells may be used, or combination of shells and convolute winding of paper ribbon, to form the finished cap, according to the strength and rigidity and decoration desired. The several shells or ribbon portions should be secured together effectively by means of adhesive or other suitable material that will form a substantial rigid structure, even though made up of relatively thin paper sections. By impressing one thread into a preceding thread groove, either by using multiple shells or convolutely wound paper ribbon in combination with a shell or shells, a rigid thread is produced on the inside of the cap which has perfect stability in resisting the thrust of glass or other threads on containers, and which thread thus formed is much more rigid with greater stability than if formed by a single operation impressed through the multiple thickness, thus forming the surrounding wall. This would not be possible if formed of cardboard or other heavy paper.

The closures made heretofore have required a liner of suitable material for sealing the contents of the container. By coating, if desired, the full shell on the inner side with a suitable material, indicated at 17 in Fig. 9, it is unnecessary to insert a liner therein, and this has the advantage of offering resisting surfaces on the side wall cap,

as well as on the liner portion. This side wall protection is not possible with metal caps, except at excessive cost.

I claim:

1. A process of making closure caps comprising forming a shell of relatively thin paper, with a top wall portion and a surrounding wall thereon, impressing a thread groove in the periphery of said wall, surrounding said wall with a second wall portion of relatively thin paper material, and thereafter impressing a thread groove in said second portion and into the first-mentioned thread groove.

15 2. A process of making closure caps comprising forming a shell of relatively thin paper, with a top wall portion and a surrounding wall thereon, impressing a thread groove in the periphery of said wall, surrounding said wall with a second wall portion of relatively thin paper material, thereafter impressing a thread groove in said second portion and into the first-mentioned thread groove, and thereafter surrounding the second wall portion with a cylindrical cover that extends over the thread grooves and conceals the same.

30 3. A process of making closure caps comprising shaping a shell of relatively thin paper to form a top portion with a depending surrounding wall, impressing a thread groove in the periphery of said wall to form a thread within the cap, forming a second shell of relatively thin paper having a top and a depending surrounding wall with smooth inner and outer surfaces, telescoping the second shell over the first-mentioned shell, and impressing a thread groove in the wall of the second shell and into the thread groove of the first-mentioned shell.

35 4. A process of making closure caps comprising shaping a shell of relatively thin paper to form a top portion with a depending surrounding wall, impressing a thread groove in the periphery of said wall to form a thread within the cap, forming a second shell of relatively thin paper having a top and a depending surrounding wall with smooth inner and outer surfaces, telescoping the second shell over the first-mentioned shell, adhesively securing said shells directly together in permanent relation, impressing a thread groove in the periphery of the wall of the second-men- 40 tioned shell and into the first-mentioned thread groove, and surrounding the wall of the second-mentioned shell with a covering extending over the thread groove and having a smooth peripheral surface for concealing said thread groove.

45 5. A process of making a closure cap comprising forming a shell from a sheet of relatively thin non-metallic material by turning over the surrounding edge to form a surrounding wall on the top portion of the shell, thereafter impressing a thread groove in said surrounding wall, thereafter surrounding said wall and thread groove with a second wall portion of thin non-metallic material, and impressing a thread groove in the second wall portion after application to the first-mentioned 50 wall and into the first-mentioned thread groove.

60 6. A process of making a closure cap comprising forming a shell of relatively thin paper with a top wall portion and a surrounding wall thereon, impressing a thread groove in the periphery of said surrounding wall, surrounding said wall with a second wall portion of relatively thin paper, thereafter impressing a thread groove in the sec- 65 ond wall portion and into the first-mentioned thread groove, and applying an end of a paper strip directly to the periphery of the second wall

portion and winding said strip thereon to form a convolute wall portion.
